SPRING MANUFACTURE

William F. Pioch and George Pascoe, Detroit,
Mich., assignors to Ford Motor Company, Dear-
born, Mich., a corporation of Delaware

Application July 19, 1946, Serial No. 684,982

8 Claims. (Cl. 266—4)

1

This invention relates to the forming and heat-treatment of leaf springs of the general type used in the construction of automobiles; and, more particularly, to a method and device therefor in which high-frequency electrically induced current is used as the heating means, and the forming and heat-treatment is effected in a continuous process.

Heretofore the forming of leaf springs to the prescribed curvature and their heat-treatment has been an expensive and difficult manufacturing operation. The character of the steel used and the thickness of the stock required the use of considerable force in forming the leaves to the desired accuracy and it was difficult to provide subsequent heat-treatment without deviation from the curvature so established. It has, therefore, been the practice to form these springs initially and restrain them in heavy presses while undergoing quenching to obtain the desired metallurgical characteristics, thus preventing warpage or change in the established curvature. This required equipment of considerable complexity and it was difficult to establish a flexible manufacturing routine or one which might be carried out in a minimum of time with elements—as they then were—of such size and weight. Moreover, the spring was subject to surface deterioration during the heating and quenching steps because of the necessary slowness of the process and it was extremely difficult to obtain the desired metallurgical characteristics and at the same time maintain the preferred spring form. A further contributing difficulty was that the springs were often not of uniform curvature or of uniform thickness, since the ends are frequently feathered or departed in other ways from a true circular curve.

The object of this invention is to devise a method for the forming and heat-treatment of leaf springs in which the operation may be conducted automatically and in a continuous step. A further object of the invention is to devise a leaf-spring forming and heat-treating apparatus and method of operation thereof employing as the heat source a high-frequency alternating electrical current. Still another object of this invention is to devise an integrated method by means of which the spring stock may progress automatically and at a uniform rate through a heating, bending, reheating, and quenching operation forming the completed spring with a minimum of surface deterioration and with the maintenance of the prescribed degree of dimensional accuracy. Still another object of this in-

2

vention is to devise a leaf spring forming and heat-treating apparatus having a high capacity of output for its size which will require a minimum of attention in operation and avoid the use of the heavy presses heretofore thought necessary.

The advantages of this method and apparatus are believed to be apparent at once to those who have worked in this art. The entire forming and heat-treating unit is compact and simple to operate. It is automatic in its function and merely requires the supplying of flat leaf blanks, which may or may not have feathered ends, and which delivers after appropriate treatment—a finished leaf having the desired curvature throughout, heat-treated, cooled, and ready for assembly. Perhaps one of the principal advantages is the relative speed of operation by which the leaf is formed and heat-treated as compared with the former methods of using the ordinary clamping devices.

Other advantages will be apparent from the invention as described in this specification, claimed in the following claims, and shown in the accompanying drawing in which:

The figure shows a partial transverse vertical section of the spring-treating device of this invention.

Referring to the drawing, 10 indicates a housing, the lower portion 11 of which is fluid-tight and contains a bath 12 of the quenching coolant. Mounted between the walls of the housing 10 in the order of operation is an array comprising the following principal elements: Stock feed 13, initial heating coil 14, initial bending mechanism 15, final heating coil 16, final bending mechanism 17, quench apparatus 18, and cooling and delivery conveyor 19. The spring leaves 20 are cut to length in the usual manner, formed with their ends feathered longitudinally as at 22 and transversely as at 21. These blanks are fed from the exterior of the housing 10 between the driven rollers 23 of the stock feed apparatus 13 which project the stock forwardly and through the induction coils 24 making up the initial heating coil 14. These are energized with alternating current (the source of which is not shown, since it may be of any conventional type), supplying current of a frequency suited to the physical characteristics of the stock being heated. The speed of the stock feed device 13 and the subsequent driving devices are synchronized so that the stock is heated sufficiently in the primary coil so that it may be bent to the desired curvature with a minimum of impressed force.

As the stock 20 emerges from the initial coil, it is engaged by the initial bending mechanism 15 which constitutes a driven roller 25 and a fulcrum roller 26 which is mounted on the fixed axis 27. An arm 28 is also pivoted on the fixed axis 27 and carries a pilot roller 29 normally urged into contact with the driven roller 25 by a spring 30 secured to the housing 10. A limit switch 32 is associated with an extension 33 of the arm 28 and is so arranged as to be responsive to the thickness of stock passing between the driven roller 25 and the pilot roller 29. The upper fixed axis 34 supports the L-shaped upper arm 35 which carries the bending roller 36 and a cam follower 37 mounted on the long leg of the L. The follower 37 engages the primary cam 39 rotatable on the axis 40 and carrying a secondary cam 42 which is associated with the secondary follower 43 cooperating with the secondary limit switch 44. The purpose of this apparatus is to permit control of the bending imparted to the spring with due regard to variation in thickness, because of the feathered ends 22 referred to above. It will be apparent that by change of the relative position of the fulcrum roller 26 and the bending roller 36 in conjunction with the driving roller 25, the degree of curvature imparted to the stock traveling between the rollers may be varied. Otherwise, when the thickness of stock varies, as it does here at the feathered ends, the curvature would change accordingly, if the rollers were fixed and it is the purpose of this apparatus to make due allowance with regard to such changes of stock thickness and also to provide different degrees of curvature at different points in the spring should this be desired.

As shown in the drawing, the cooperating rollers are arranged to impart a desired uniform curvature to the midpart or constant thickness extent of the spring leaf, and the cam follower 37 is on the minimum circular extent 38 of the primary cam 39. It will be apparent that as the primary cam 39 rotates past 90° from the position shown in the drawing, the effective radius of the cam 39 increases in the linear sections 41, and the cam follower 37 will be moved, displaced in a counterclockwise direction with reference to the axis 34, while the bending roller 36 will be projected in the same direction increasing the relative curvature of the curved line determined by the working faces of the rollers 25, 26, and 36, and tending to increase the relative curvature of stock operated upon by these rollers, thus allowing for the relative variation in stock thickness through the feathered portion 22. The maximum circular extent 45 of the cam 39 corresponds to the alignment of the bending rollers when no stock is passing through them. The operation of the cam 39 is governed by the limit switch 32 and as the initial edge of the stock enters between the driven roller 25 and the pilot roller 29 forcing them apart, the limit switch is activated and begins to revolve the cam 39 from the position 180° from that shown in which the cam follower 37 is on the maximum circular extent 45 to one in which one of the linear sections 41 of the cam 39 engages the follower 37 and progressively decreases the obliquity of the bending roll 36, as the feathered end 22 of the spring blank passes beneath it. The relative position of the working rolls thus changes automatically to compensate for decreased thickness due to the feathered end, and thereby imparts a uniform curvature to the entire blank or may even provide such additional curvature at the ends as may be desired depend-

ing on the cam outline. The effective sequence of rotation of the primary cam 39 is governed by the secondary cam 42 and its follower 43 and the secondary limit switch 44 which may be adjusted to compensate for the various lengths of springs or feathered ends to be handled and the degree of corrective or excess curvature required. The cam 39, as shown, is somewhat exaggerated for the purpose of this showing, but the actual design to obtain the desired bending roller displacement and length of dwell between blanks or during operation on uniform sections is a simple matter of mechanical design.

Thus, as the stock initially enters the bending mechanism, its forward speed is so synchronized that when its forward end reaches the bending roller 36, the position of that roller is such as to accommodate minimum thickness of the stock, i. e. with the follower 37 on the maximum circular extent 45 and the cam rotates in synchronism with the stock as it passes under the bending roller, the follower 37 engages the following linear section 41 of the cam 39 corresponding to the length of the feather 22 and progressively changing the position of the bearing roller 36 as the obliquity of the cam 39 decreases so that the follower 37 enters on the minimum circular extent 38 as the full thickness of the stock comes to the roller 36. The same operation, but in reverse, is effected when the rear feathered end is reached. The secondary limit switch 44 co-operating with the secondary cam effects the maintenance of the proper time relationship required of the cam 39 commensurate with the length of the spring and feathered end the distance between successive pieces of stock, being interlocked appropriately with the primary limit switch 32.

The bent stock then passes through a secondary heating coil 16 adjusted to raise its temperature above the critical point of the steel, as may be required to obtain the desired metallurgical characteristics. It is then subjected to a final bending step in the mechanism 17 which, in construction, is substantially the same as that of the initial bending mechanism described above, to correct the spring shape after the secondary heating and to hold it in prescribed curvature as the quenching operation progresses. It will be apparent that provision must be made here, as well, for the variation in stock thickness due to the feathered ends and the stock must be rigidly held when the quench is applied if the desired curvature is to be obtained. The final bending mechanism 17 will not be described in detail, nor is it so shown, since it is substantially the same as the initial bending mechanism 15. It may suffice to say that it has as corresponding parts, the driven roller 47, pilot roller 48, bending roller 49, arm 50, primary limit switch 52, L-shaped arm 53 and fulcrum roller 54. The cam follower 55 is shown above the associated cam mechanism and secondary limit switch corresponding to that described in detail under the primary bending mechanism is omitted from this showing, although it will be understood that it is of substantially the same construction.

It is thus apparent that as the heated spring emerges from the secondary heating coil 16, it is re-engaged by the final bending mechanism 17 which restores it to the desired precise curvature with due respect to the variation in stock thickness and that it is subsequently held in this position as it is quenched so that curvature is maintained in the finished leaf. The quenching fluid 75 is projected on the heated leaf from the headers

56 and 57 from which a number of individual quench pipes 58 lead to the proximity of the spring blank and are so directed as to provide a uniform distribution of the quenching fluid. The headers 56 and 57 are supplied with the coolant fluid from the pump 59 which withdraws it from the bath 12 through the separation chamber 60. After the coolant fluid has been projected on the work, it flows back into the bath and is recirculated. It will also be noted that two initial quench pipes 62 and 63 are located between the driven roller 47 and the fulcrum roller 54 of the secondary bending mechanism 17. Thus, the heated material as it emerges from the secondary coil is given a partial quench before being bent to the finished curvature which is often of considerable value in insuring that the desired curvature is, in fact, obtained.

As the stock leaves the secondary bending machine 17, it is engaged between a series of opposed rollers 64, certain of which such as 61 are driven, and the whole array is fixed in a prescribed relative curvature so that the spring while passing through them is continuously restrained in the conformation desired. The quench coolant is continuously ejected on the stock during this stage so that it is cooled below the critical point with the speed necessary to obtain the desired metallurgical characteristics. The relative curvature of the array may be changed by suitable adjustment of the axes of the various rollers through any conventional means so that springs of various radii may be treated. It will be noted that no special provision is made here to allow for the variation of stock thickness accounted for by the feathered end, since these—being quite thin—are speedily cooled and stabilized and the prime function of the rollers 64 is to prevent gross warpage in the main body of the spring until the quench is completed. The springs are of course restrained by rollers 64 until cooled sufficiently to preclude any substantial warpage. The rollers 64 are, preferably, somewhat narrower than the stock and appropriately staggered, transversely, to allow access of coolant to the spring.

As the stock leaves the quenching apparatus 18, it is projected through the delivery rollers 65, at least one of which is driven as at 68, and enters the bath 12 where it is directed so that it falls on the delivery conveyor having the receiving flight 66 and return flight 67. These are preferably inclined to the plane of the drawing and carry the cooled spring up and out of the bath for delivery. Further details of this construction are not deemed necessary for the purpose of this application, since the conveyor design is conventional.

It will thus be seen that provision is made for automatic heating, bending, quenching and holding during the quench period as well as such further cooling as may be required to obtain a spring leaf of precise dimension and the metallurgical characteristics required. This is all done automatically and with a minimum of attention or care. Proper allowance is made for variations in thickness of the stock and it is possible to provide for different curvatures by suitable arrangement of these bending control means. The advantage of such an arrangement is believed to be manifest.

We realize that certain changes may be made in the apparatus and method of operation thereof as described above and it is the intention to cover in the following claims such of these changes as are reasonably within the scope thereof.

The invention claimed is:

1. In an apparatus for forming and heat-treating a steel spring leaf, a linear array, comprising, a high frequency electrical heating coil, a bending means, a restraining means, a quenching means to direct coolant past said restraining means and to the spring leaf, and means to travel said spring leaf longitudinally through said array.
2. In an apparatus for the forming and heat-treating a steel spring leaf, a linear array, comprising, a high frequency electrical heating coil, a bending means, a secondary high frequency electrical heating coil, a secondary bending means, a restraining means, a quenching means to direct coolant past said restraining means and to the spring leaf, and means to travel said spring leaf longitudinally through said array at a substantially uniform speed.
3. In an apparatus for the forming and heat-treating a steel spring leaf, a linear array, comprising, a high-frequency electrical heating coil, a bending means, a restraining means, a quenching means, means to direct coolant past said restraining means and to the spring leaf, means to travel said spring leaf longitudinally through said array at a substantially uniform speed, and means to vary the degree of curvature imparted to said leaf by said bending means in relation to the thickness of said leaf.
4. In an apparatus for the continuous forming and heat-treating of a steel spring leaf, a linear array, comprising, a high-frequency electrical heating coil, a bending means, said bending means being automatically variable to impart a uniform circular curvature to said stock as it passes therebetween despite variations in the thickness of said stock, a secondary heating means effective to raise said stock as it travels therethrough above the critical temperature of said steel, an initial quenching means effecting said heated stock, a secondary bending means effective to bend said stock to said prescribed curvature at the said initial quench, a restraining means comprising a series of oppositely arranged rollers having their axes fixed to establish said prescribed circular curvature and progressively engaging said stock as it emerges from said second bending mechanism, quenching means to direct coolant past said restraining means to said stock as it passes therethrough, and means to travel said spring leaf longitudinally through said array at a substantially uniform speed.
5. In an apparatus for forming and heat-treating a steel spring leaf, a linear array, comprising, a high-frequency electrical heating coil, a bending means comprising alternate rollers mounted on opposite sides of said leaf and axially displaced to impart circular curvature to the leaf passing therebetween, a restraining means and to the spring leaf, a quenching means to direct coolant to said restraining means, and means to travel said spring leaf longitudinally through said array at substantially uniform speed.
6. In an apparatus for forming and heat-treating a steel spring leaf, a linear array, comprising, a high-frequency electrical heating coil, a bending means comprising alternate rollers on opposite sides of said leaf axially displaced to impart circular curvature to said leaf as it passes therebetween, means to vary automatically said axial alignment of said rollers with respect to the thickness of said leaf to impart a substantially uniform circular curvature thereto, a restraining means, a quenching means to direct coolant to

said restraining means and to the spring leaf, and means to travel said spring leaf longitudinally through said array at a substantially uniform speed.

7. In an apparatus for forming and heat-treating a steel spring leaf, a linear array, comprising, a high-frequency electrical heating coil, a bending means comprising alternate rollers on opposite sides of said leaf axially so arranged as to impart a circular curvature to the leaf passing therethrough, a secondary heating means, a secondary bending means, a series of opposed rollers adapted to engage said leaf as it emerges from said second bending means and having their respective axes arranged in a predetermined circular curvature, quenching means directing coolant past said restraining means and to the spring leaf to quench said leaf as it passes therethrough, and means to travel said spring leaf longitudinally through said array at a substantially uniform speed.

8. In an apparatus for forming and heat-treating a steel spring leaf, a linear array, comprising, a high-frequency electrical heating coil, a bending means engaging said spring as it emerges from said coil, a secondary heating means engaging said leaf as it emerges from said bending means and adapted to heat said leaf above the critical temperature, an initial quenching means partially quenching said leaf as it emerges from said secondary heating means, a secondary bending means engaging said leaf as it emerges from said initial quench and bending it to finished

10 5 curvature, a series of oppositely arranged rollers having their respective axes following said circular curvature and adapted to engage said leaf therebetween as it emerges from said secondary bending means, a final quenching means to direct coolant past said restraining means and to the spring leaf while said leaf is passing therethrough, and means to travel said spring leaf continuously through said array.
